[57] ABSTRACT

A device for displaying a lighted gasoline lantern from a small pleasure boat, usually powered by an outboard engine, having hand rails conveniently located near peripheral edge portions of the boat. The holder of the invention is designed to be suspended from such a hand rail, some of which are positioned in close proximity to the boat and extend horizontally. Other such

hand rails are comparatively high, or extend vertically as well as horizontally. The invention is also adapted to be suspended from cleats of the type which are provided for securing lengths of rope to a boat, as in securing the boat or for whatever reason.

The lantern holder of the invention, which is adjustable for use with lanterns of different sizes, includes a cylindrical receptacle, comparatively short relative to its diameter, which in use is disposed vertically and has the bottom of a lantern received bodily therein, and an elongated metal strip, preferably aluminum, characterized by its inherent spring tension but soft and easily bent, which has a hook or loop formed in one of its end portions and in use is secured about a hand rail as described, from which the strip is suspended. The depending end portion of the strip has means removably and adjustably connecting it to the receptacle, to support the receptacle on the hand rail at a predetermined distance below it. An extra long strip having a twist therein is provided for use with hand rails which are comparatively high and which are inclined at any angle relative to the horizontal plane. Detent means, rigidly and removably connected to an intermediate portion of the strip and adjustable longitudinally relative thereto, is provided for selective engagement by the bail or handle of a lantern having its bottom in place in the receptacle, to prevent accidental displacement thereof.

HOLDER FOR GASOLINE LANTERN

This invention relates to a holder for a gasoline lantern, and it concerns more particularly a device as hereinafter described for displaying a lighted gasoline lantern from a small pleasure boat, usually powered by an outboard engine, having hand rails conveniently located near peripheral edge portions of the boat.

The holder of the invention is designed to be suspended from such a hand rail, some of which are positioned in close proximity to the boat and extend horizontally. Other such hand rails are comparatively high, or extend vertically as well as horizontally. The invention is also adapted to be suspended from cleats of the type which are provided for securing lengths of rope to a boat, as in securing the boat or for whatever reason.

An object of the invention is to provide a holder for suspending a gasoline lantern from a hand rail of such a boat, or from a cleat or other like device conveniently located on a boat, at night, usually when the boat is secured or at anchor, not in motion, as while fishing, or as a safety precaution, or for any reason that a lantern may be needed.

The lantern holder of the invention, which is adjustable for use with lanterns of different sizes, includes a cylindrical receptacle, comparatively short relative to its diameter, which in use is disposed vertically and has the bottom of a lantern received bodily therein, and an elongated metal strip, preferably aluminum, characterized by its inherent spring tension but soft and easily bent, which has a hook or loop formed in one of its end portions and in use is secured about a hand rail as described, from which the strip is suspended.

The depending end portion of the strip has means removably and adjustably connecting it to the receptacle, to support the receptacle on the hand rail at a predetermined distance below it. An extra long strip, or one having a twist therein, is provided for use with hand rails which are comparatively high, or inclined at any angle relative to the horizontal plane.

Detent means, rigidly and removably connected to an intermediate portion of the strip and adjustable longitudinally relative thereto, is provided for selective engagement by the bail or handle of a lantern having its bottom in place in the receptacle, to prevent accidental displacement thereof.

The invention will be readily understood by referring to the following description and the accompanying drawing, in which:

FIG. 1 is a sectional elevational view showing fragmentarily a gunwale of a boat having a hand rail above it; showing a holder for a gasoline lantern embodying the invention in its operative position as applied to the hand rail, and showing a lantern in place in the holder;

FIG. 2 is a side elevational view of the holder;

FIG. 3 is a view similar to FIG. 1 showing the holder as applied to a hand rail which is comparatively high;

FIG. 4 is a fragmentary view showing the holder as applied to a hand rail which is inclined relative to the horizontal plane; and

FIG. 5 is a fragmentary view showing the holder as applied to a vertically extending hand rail.

Referring to the drawing, the numeral 10 designates generally a gunwale, shown fragmentarily, which is rep-

resentative of the gunwales of small pleasure boats now in use, and which are usually powered by outboard engines. FIG. 1 shows a hand rail 11 which extends horizontally above the top of the gunwale 10, to which the holder of the invention is applied, as hereinafter described. FIG. 3 shows the holder applied to a hand rail 11 which is comparatively high. As shown in FIG. 4 the hand rail 11 is inclined relative to the horizontal plane, and in FIG. 5 the hand rail 11 extends vertically.

The numeral 20 designates generally a conventional gasoline lantern having a cylindrical fuel tank 21 at the bottom, and having a bail or handle 22 at the top, and the numeral 30 indicates generally a holder for the gasoline lantern 20 embodying this invention.

The holder 30 includes a cylindrical receptacle, indicated by the numeral 40, which is comparatively short relative to its diameter, and which in use is disposed vertically and has the bottom 21 of a lantern 20 received bodily therein, and an elongated metal strip 50 which is characterized by its inherent spring tension but is soft and easily bent, and which advantageously may be made of aluminum.

The strip 50 has a 180 degree bend in one of its end portions, as at 51, forming a hook or loop thereon which in use is secured about a hand rail 11 as variously illustrated in the drawing. As shown a bolt 52 is passed through openings therefor in two thicknesses of the strip 50 on opposite sides of the "U" bend 51, to prevent accidental displacement of the strip 50 relative to the hand rail 11, from which it is suspended.

The depending end portion of the strip 50 has means removably and adjustably connecting it to the receptacle 40, to support the receptacle 40 on the hand rail 11 at a predetermined distance below it. As shown in FIG.

3 an extra long strip 50 is provided for use with a hand rail 11 which is comparatively high. As shown in FIGS. 4 and 5 the strip 50 has a twist in it for use with a hand rail 11 which is inclined at any angle relative to the horizontal plane.

The depending end portion of the strip 50 has a longitudinal slot 55 therein for engagement by bolts 56 whereby the strip 50 is removably and adjustably connected to an opposing slide element 60, which has a corresponding slot 61 therein for engagement by the bolts 56 and is removably and adjustably connected by bolts 56 to one side of the receptacle 40.

Detent means as hereinafter described, rigidly and removably connected to an intermediate portion of the strip 50, and adjustable longitudinally relative thereto, is provided for selective engagement by the bail or handle 22 of a lantern 20 having its bottom in place in the receptacle 40, to prevent accidental displacement thereof.

The detent means above mentioned includes a pair of shaped companion members 70, 80, as hereinafter described, each of them consisting of an elongated, substantially rectangular plate bent right angularly intermediate its ends. The member 70 is "L" shaped and the member 80 is "U" shaped. The members 70, 80 are arranged one upon the other on the intermediate portion of the strip 50, and are connected thereto by a bolt 90, which is surrounded by an elongated bearing 91 and has a wing nut 92 thereon.

The intermediate portion of the strip 50, and an end portion of the "L" shaped member 70, have longitudinal slots 95, 96 therein, and a corresponding hole is

provided in the middle portion of the "U" shaped member 80, for engagement by the bolt 90.

The opposite end portions of the "U" shaped member 80 each have indentations in one of their longitudinal edges, as at 99, in opposing relation to an end portion of the "L" shaped member 70, for selective engagement by a bail or handle 22 of a lantern 20 having its bottom 21 in place in the receptacle 40. In use the bail or handle 22 is hooked over the "U" shaped member 80, and the "L" shaped member 70 acts as a keeper, to prevent accidental displacement of the bail or handle 22 from the indentations 99 of the "U" shaped member 80.

I claim:

1. In a device for displaying a lighted gasoline lantern from a small pleasure boat, usually powered by an outboard engine, having hand rails conveniently located near peripheral edge portions of the boat, the combination of a cylindrical receptacle, comparatively short relative to its diameter, which in use is disposed vertically and has the bottom of a lantern received bodily therein, an elongated metal strip, characterized by its inherent spring tension but soft and easily bent, which has a hook or loop in one of its end portions and in use is secured about a hand rail as described, from which the strip is suspended, the depending end portion of the strip having means removably and adjustably connect-

ing it to the receptacle, to support the receptacle on the hand rail at a predetermined distance below it, and detent means, rigidly and removably connected to an intermediate portion of the strip and adjustable longitudinally relative thereto, for selective engagement by the bail or handle of a lantern having its bottom in place in the receptacle, to prevent accidental displacement thereof.

2. The structure of claim 1, the detent means above mentioned including a pair of shaped companion members, each consisting of an elongated, substantially rectangular plate bent right angularly intermediate its ends, one of the shaped members being "L" shaped and the other of the shaped members being "U" shaped, the shaped members being arranged one upon the other on the intermediate portion of the strip, and being connected thereto by a bolt, the intermediate portion of the "U" shaped member having a hole therein for engagement by the bolt, which is also passed through longitudinal slots therefor in the strip and in an end portion of the "L" shaped member, the opposite end portions of the "U" shaped member having indentations in one of their longitudinal edges, in opposing relation to an end portion of the "L" shaped member, for selective engagement by a bail or handle of a lantern having its bottom in place in the receptacle.
